(57) **CLAIM**

We claim the ornamental design for the clip assembly, as shown and described.

DESCRIPTION

FIG. 1 is a front, left perspective view of an clip assembly in a closed position showing our new design.

FIG. 2 is a front, right perspective view thereof.

FIG. 3 is a top view thereof.

FIG. 4 is a bottom plan view thereof.

FIG. 5 is a right side plan view thereof;

FIG. 6 is a left side plan view thereof.

FIG. 7 is front plan view thereof.

FIG. 8 is a rear plan view thereof.

FIG. 9 is a front, left perspective view of the clip assembly in an open position.

FIG. 10 is a front, right perspective view of the clip assembly in an open position.

FIG. 11 is a top plan view of the clip assembly in an open position.

FIG. 12 is a right side plan view of the clip assembly in an open position.

FIG. 13 is a left side plan view of the clip assembly in an open position.

FIG. 14 is a front plan view of the clip assembly in an open position.

FIG. 15 is a rear plan view of the clip assembly in an open position; and,

FIG. 16 is an exploded, front, left perspective view of the clip assembly.
